UNITED STATES PATENT OFFICE

2,512,434

VAGINAL IRRIGATOR

Joseph Anton Leu, Basel, Switzerland

Application April 7, 1947, Serial No. 739,913
In Switzerland April 25, 1945Section 1, Public Law 690, August 8, 1946
Patent expires April 25, 1965

1 Claim. (Cl. 128—244)

1

The present invention relates to vaginal irrigators or syringes of the type having a canula or nozzle which is surrounded by a widening device and having a setting member to limit the depth of penetration of the nozzle.

An object of the present invention is to provide a vaginal irrigator having adjustable spreader arms constituting a widening device.

Another object of the present invention is to provide a vaginal irrigator having a widening device and a depth penetrating regulating member, the widening device and the setting member being operable separately without affecting the setting of the other.

The improved vaginal irrigator of the present invention is characterized by the fact that the depth penetrating setting member is movable in an axial direction with relation to the nozzle and the associated widening device in such a way that by relative displacement between these parts the desired depth of penetration of the nozzle can be regulated and thereafter the widening device and the depth penetration setting member can be secured relatively to one another.

The present invention will be better understood by reference to the accompanying drawing in which the figure is a longitudinal section of a preferred embodiment of the present invention.

Referring specifically to the drawing, the vaginal irrigator shown has a nozzle *a* having a plurality of openings therein and a head so that the fluid passing therethrough can be applied to the desired area. This nozzle can be made of any suitable material such as for example glass. At the rearward end of the nozzle *a*, a spigot member *a*¹ for attachment thereto of the rubber hose *b* having the rubber bulb *b*¹ therein is provided. Fluid enters the nozzle through the rubber hose *b* as indicated by the arrow adjacent to the bulb *b*¹.

In order to enable the walls of the vagina to be spread or dilated for the purpose of ensuring a thorough washing or injection of the injected fluid there are arranged spreader arms *c* adjacent to the nozzle *a* on at least two sides thereof and which spreader arms *c* together form the widening device. These spreader arms *c* are pivotally mounted in the boxlike carrier *d* by means of the member *d*¹. The carrier *d* is round in cross section. The rearward portions of the spreader arms *c* are fastened to a screw threaded sleeve *e*

2

by means of links *e*¹. The sleeve *e* is slidably mounted on the inner end portion of the nozzle *a*. A finger nut or the like *f* is screwed onto the sleeve *e* and extends into the carrier *d*. By means of the finger nut *f* being rotated the sleeve *e* can be axially displaced with relation to the nozzle whereby the spreader arms *c* can be moved away from the nozzle *a* as shown in dotted lines in the figure or moved inwardly towards the nozzle.

10 The oval plate shaped depth penetration setting member *g* having a hollow cylindrical skirt *g*¹ is slidably mounted upon and guided by the carrier box *d*. This skirt *g*¹ has longitudinal slots *g*² in the sides thereof. Clamping screws *h* pass through the longitudinal slots *g*² and are screwed into the pivot member *d*¹. The setting member *g* can be displaced axially upon the carrier box *d* due to the provision of the slots *g*² and secured in any desired position of adjustment by means of the screws *h*. In this manner the depth of penetration of the nozzle *a* can be regulated as desired which is of particular advantage and yet the spreader arms constituting the widening device can be operated without affecting the setting of the member *g*.

15 The washing or irrigating water or fluid is delivered to the nozzle *a* in the known manner by alternate squeezing or release of the rubber bulb *b*¹. An outlet pipe *i* is provided in the setting member *g* so that the water or fluid can flow away during use of the irrigator as shown by the arrow adjacent to the pipe *i* in a known manner.

20 It is apparent that modifications may be made in the described preferred embodiment of the invention without departing from the scope of the appended claim defining the limits of my invention.

25 What I claim is:

A vaginal irrigator comprising a hollow carrier, 40 a nozzle secured in said carrier and extending therefrom, spreader arms pivotally mounted in said carrier and extending substantially parallel to said nozzle, adjusting means for moving said spreader arms toward or away from said nozzle comprising an externally threaded sleeve movably mounted on said nozzle in said carrier member, links connecting said sleeve and said spreader arms, an internally threaded adjusting member 45 screwed to said sleeve and rotatably journaled in a wall of said carrier for moving said sleeve

and spreading said arms, a depth penetration setting member having an oval shaped opening and a skirt thereon having longitudinal slots therein, said setting member being slidably mounted on said carrier, and clamping screws inserted in said carrier through said slots in said setting member for securing said setting member in desired relationship with said carrier and said nozzle, said setting member and said spreader arms being respectively adjustable without affecting the setting of the other.

JOSEPH ANTON LEU.
